[57] CLAIM

The ornamental design for a car body, as shown and described.

DESCRIPTION

FIG. 1 is a front elevational view of a car body showing my new design;

FIG. 2 is a left side elevational view of FIG. 1, the right side being substantially a mirror image thereof;

FIG. 3 is a rear elevational view of FIG. 1; and

FIG. 4 is a left front perspective view of FIG. 1. The broken lines in the drawing are for illustrative purposes only.
